UNITED STATES PATENT OFFICE.

HIRAM PERCY MAXIM, OF HARTFORD, CONNECTICUT, ASSIGNOR TO MAXIM SILENT FIREARMS COMPANY, OF NEW YORK, N. Y., A CORPORATION OF NEW JERSEY.

SILENT FIREARM.

958,935.

Specification of Letters Patent. Patented May 24, 1910.

Application filed November 30, 1908. Serial No. 465,051.

To all whom it may concern:

Be it known that I, HIRAM PERCY MAXIM, a citizen of the United States, residing in the city of Hartford, in the State of Connecticut, have invented certain new and useful Improvements in Silent Firearms, of which the following is a specification, reference being had to the accompanying drawing, forming a part hereof.

10 In the continued use of silencers for firearms in which the energy of the powder gases is dissipated in rotary or whirling movement of the gases before they pass into the atmosphere, and in which a series of partitions, diaphragms or spreaders are supported by a shell or casing at the muzzle of the firearm, the rotary or whirling movement of the gases taking place in the chambers formed thereby, the partitions, diaphragms or spreaders nearest the true muzzle of the barrel of the firearm are exposed to the highest gas pressure, while those more remote from the muzzle are exposed to much less gas pressure. Lightness in the silencer 20 can be secured by making the partitions, diaphragms or spreaders in the zone of high gas pressure of sufficient strength to withstand such pressure and by making the partitions, diaphragms or spreaders more remote 25 from the muzzle of thinner and even of lighter material. It is found, however, that it is necessary to provide an abutment for the heavier and stronger diaphragms near the muzzle to support them against the impact of the gases and to relieve from great pressure the successive lighter diaphragms, which are liable to be crushed eventually if the resistance is through them.

30 One object of the present invention, therefore, is to provide such a construction of silencers of this character as shall be capable of withstanding the impact of the gases while at the same time the minimum of weight in the silencers is secured. Furthermore, in silencers of this character which are eccentric with respect to the axis of the gun barrel, it is necessary to assure accurate alinement of the openings through the successive diaphragms for the passage of the 40 projectile.

It is, therefore, a further object of this invention to provide a construction by which such alinement of the openings through the

diaphragms shall be secured without requiring great labor in the assembling of the diaphragms and casing. 55

The invention will be more fully explained hereinafter with reference to the accompanying drawing in which it is illustrated and in which— 60

Figure 1 is a view in side elevation of an ordinary sporting rifle equipped with a silencer which embodies the invention. Fig. 2 is a detail view in section and on a larger scale of the silencer shown in Fig. 1, a portion of the barrel being also represented. Fig. 3 is a face view of one of the diaphragms, showing the recesses in the circumference thereof. Fig. 4 is a transverse section of the supporting shell or casing, 70 showing the longitudinal key.

In the embodiment of the invention shown in the drawing there is secured to the extremity of the barrel *a* of the gun, in any suitable manner, as by screw threads, a casing *d*, which is preferably substantially circular in cross section and of greater or less length as may be required and forms a support and inclosure for the series of single silencing devices or partitions or diaphragms 80 or spreaders *e* by which the gases, which escape at the muzzle of the barrel *a*, are compelled to acquire, within successive cells or chambers formed by the diaphragms *e*, a rotary or whirling movement. 85

In the embodiment of the invention shown each single silencing device *e* is generally circular or annular with reference to the axis of the shell or casing *a*, and is spiral or conchoidal in cross section, an opening *e'* 90 being formed for the passage of the projectile. In the construction shown, such opening is eccentric with respect to the axis of the shell or casing. As is now well understood, the powder gases are directed by 95 the frusto-conical portion of each diaphragm or spreader, or single silencing device, into the annular chamber formed by the diaphragm and acquire therein a rapid rotary motion in which their energy is dissipated. The diaphragms or spreaders, as *e²*, nearest the muzzle of the gun are naturally subjected to the highest pressure of the gases, while those more remote from the muzzle are subjected to a considerably lower 100 pressure. Those more remote from the

muzzle of the gun may, therefore, be less capable of resisting high pressure than those nearer the muzzle and may be made of much lighter sheet steel than those near the 5 muzzle, or may even be made of aluminum, while those nearer the muzzle are made of steel. However, should the diaphragms or spreaders nearer the muzzle rest directly against those more remote from the muzzle, so that the latter receive the pressure transmitted through the former, they would eventually be broken down. To obviate this, an abutment is formed in the shell or casing d to receive the pressure of the diaphragms or spreaders in the zone of high 10 gas pressure. Such abutment may be variously formed, but as a convenient and inexpensive, but effective construction, the shell or casing d , after the lighter diaphragms or 15 spreaders e have been placed therein, is formed with an inner circumferential ridge or shoulder d' , as by spinning, and against such abutment the heavier diaphragms or spreaders e^2 rest. It will be understood 20 that the number of heavier or stronger diaphragms or spreaders employed will depend 25 upon the character of the gun to which the silencer is applied. For a light power gun it is sufficient to provide one heavy, steel diaphragm or spreader e^2 , as shown in Fig. 2 30 of the drawing, but with a gun of higher power two or more of the heavy steel diaphragms or spreaders may be required. Of course the number of the lighter diaphragms 35 or spreaders employed will also depend upon the character of the gun to which the silencer is applied and the effect to be produced. In the construction shown in Fig. 2 40 space is provided within the shell or casing d for more than one heavy or strong diaphragm or spreader and a spacing sleeve d^2 is introduced to hold the single diaphragm or spreader in place.

It will be understood that the provision 45 of an abutment for the heavier diaphragms or spreaders is equally desirable, whether the silencer be concentric with the axis of the gun barrel or eccentric with respect thereto. In the construction shown in the drawing, however, the silencer is eccentric and it therefore becomes desirable to provide means 50 for readily assuring the accurate alinement of the openings e' in the several diaphragms or spreaders with the bore of the gun barrel. For this purpose, in the construction shown, each of the diaphragms or spreaders is provided in its circumference with a keyway, as shown at e^3 in Fig. 3, and the shell or casing d is provided with an internal 55 longitudinal ridge or key d^3 , which may be conveniently formed by rolling or pressing a suitably shaped tool into the outer wall of the casing. With this construction the diaphragms or spreaders cannot be introduced 60 into the shell or casing except in their 65

proper relative position with the openings e' in accurate alinement with the bore of the barrel a .

I claim as my invention:

1. A silencing device for firearms, comprising a shell or casing, a series of diaphragms or spreaders disposed in the shell or casing remote from the muzzle and forming a succession of chambers, each of the diaphragms or spreaders having an opening 70 for the passage of the projectile, and a relatively heavy or strong diaphragm or spreader disposed in the shell or casing adjacent to the muzzle of the firearm and also having an opening for the passage of the 75 projectile, the shell or casing having an abutment to resist the forward pressure of such heavier diaphragm or spreader, whereby the lighter diaphragms or spreaders 80 remote from the muzzle of the firearm are relieved of the pressure of the heavier diaphragm or spreader. 85

2. A silencing device for firearms, comprising a supporting shell or casing, a series of diaphragms or spreaders disposed in the shell or casing remote from the muzzle and forming a succession of chambers, each of the diaphragms or spreaders having an opening 90 for the passage of the projectile and forming an annular cell substantially conchoidal in cross section, and a heavier diaphragm or spreader disposed in the shell or casing adjacent to the muzzle of the firearm and also having an opening for the passage of the projectile and also forming an annular cell substantially 95 conchoidal in cross section, the supporting shell or casing having an abutment to receive the pressure of such heavier diaphragm or spreader, whereby the lighter diaphragms or spreaders 100 remote from the muzzle of the firearm are relieved of the pressure of the heavier diaphragm or spreader. 105

3. A silencing device for firearms, comprising a supporting shell or casing, a series 110 of diaphragms or spreaders disposed in the shell or casing remote from the muzzle of the firearm, each of the diaphragms or spreaders forming an annular cell substantially conchoidal in cross section and having 115 an opening for the passage of the projectile, and a heavier or stronger diaphragm or spreader disposed in the shell or casing adjacent to the muzzle of the firearm and also forming an annular cell substantially conchoidal in cross section and having an opening 120 for the passage of the projectile, the supporting shell or casing having an interior circumferential ridge forming an abutment to receive the pressure of such heavier diaphragm or spreader, whereby the lighter diaphragms or spreaders remote from the muzzle of the firearm are relieved of the pressure of the heavier diaphragm or spreader. 125

4. A silencing device for firearms, comprising a supporting shell or casing and a series of diaphragms or spreaders disposed in the shell or casing and forming a succession of chambers, each of the diaphragms or spreaders having an opening eccentrically disposed for the passage of the projectile, the shell or casing having an interior ridge or key and each of the diaphragms or spreaders having a key-way to coöperate therewith.

5. A silencing device for firearms, comprising a supporting shell or casing and a series of diaphragms or spreaders disposed in the supporting shell or casing and form-

ing a succession of chambers, each of the diaphragms or spreaders forming an annular cell substantially conchoidal in cross section and having an opening eccentrically disposed for the passage of the projectile, the 20 shell or casing having an interior ridge or key and each of the diaphragms or spreaders having a key-way to coöperate therewith.

This specification signed and witnessed this 27th day of November, A. D., 1908.
